LAMP SHADE ADAPTER

William N. de Sherbinin, Hastings on Hudson,
N. Y.

Application February 15, 1934, Serial No. 711,319

6 Claims. (Cl. 240—138)

This invention relates to lamps and lamp shades and more particularly pertains to a device for securing lamp shades of various types directly to electric light bulbs.

5. The invention provides an adapter which secures any standard lamp shade, that is, a washer or spider, bridge or ring type shade to an electric light bulb, regardless of the position in which the bulb is supported. The adapter 10 further permits the lamp shade to be supported on the bulb at different heights.

The nature of the invention will be understood from the following description considered in connection with the accompanying drawings forming a part thereof and in which:

Fig. 1 is a perspective view of the preferred embodiment of an adapter of the present invention;

Fig. 2 is an elevational view, partly in cross-section, showing a washer type shade secured to a bulb by the adapter of this invention;

Fig. 3 is a partial sectional view on an enlarged scale, taken substantially on line 3—3 of Fig. 2;

Fig. 4 is a partial, elevational sectional view 25 showing a ring type shade secured to a bulb by the adapter of the present invention, taken substantially on line 4—4 of Fig. 5;

Fig. 5 is a partial top plan view of Fig. 4;

Fig. 6 is a view similar to Fig. 4 but showing 30 the shade engaged by the adapter at a lower position;

Fig. 7 is a partial elevational, sectional view showing a bridge type shade secured to a bulb by the adapter; and

Fig. 8 is a partial vertical sectional view of a 35 shade secured to a bulb on a bridge type lamp base by the adapter.

Like characters of reference refer to like or similar parts throughout the several views.

40 Referring to the drawings, reference character A designates generally an adapter embodying the present invention. The adapter consists essentially of a bulb engaging portion and a lamp shade engaging portion. The bulb engaging portion 45 comprises two spaced incomplete rings 10 and 11 of resilient wire in substantial alignment with each other. The ends of the bulb engaging rings 10 and 11 are secured to the lamp shade engaging portions 12 and 13. The latter each consists

50 essentially of a rectangular metal plate 14 of suitable rigidity having a narrow extension 15 projecting from the center portion of the upper edge of the rectangular portion and lying substantially in the same plane therewith. The

55 extension 15 is provided with a laterally extending flange 16. As shown, the rings 10 and 11 are secured to the plates 14 by rolling the lateral edges of the plates around the outer end portions of the rings into secure engagement therewith.

60 The ends of the rings 17 and 18 which extend

beyond plates 14 are bent outwardly in substantially the same direction as the flanges 16. The portions 19 and 20 of the adapter which connect the bulb engaging and the shade engaging portions are, as shown, formed into substantial 5 S-shape, but this portion may otherwise be formed if desired.

The rings 10 and 11 are formed with a diameter such that they will snugly engage an electric light bulb in the manner shown in Fig. 2. 10

The dimensions of the plates 14 and the end portions of the rings 10 and 11 are such that they will readily and securely engage the inner peripheral portion of bridge or ring type shades and the dimensions of the extensions 15 are 15

such that they may readily be inserted in the relatively small apertures in a washer type shade and will securely engage the inner peripheral portions thereof. The rings 10 and 11 are 20

preferably made of resilient steel wire with sufficient 25 resiliency to permit their lower portions to be spread apart in a direction transverse to their planes and to be sprung over an electric light bulb and further to permit their end portions, or the plates 14, to be moved toward each other to the extent necessary for them to properly

engage the inner peripheral portion of the annulus of any lamp shade, whether bridge, ring or washer type. The rings 10 and 11 may be 30

made from any material suitable for the purpose and may have cross-sectional configurations, other than circular, which are suitable for the purpose intended. At such times as the adapter 35

is not in engagement with the annulus of a shade, the plates 14 are preferably disposed at a distance apart which is normally greater than the inside diameter of any lamp shade annulus to be engaged by the adapter, so that when the plates 14 are brought together and into engagement with the annulus of a shade, the rings exert a force on the plates tending to force them 40

apart and into secure engagement with the annulus.

Figs. 2 and 3 illustrate the adapter utilized for mounting a washer type lamp shade to a bulb. The bulb B is supported in an upright position 45 in a socket 21 which is mounted on a standard 22 having a base 23. The lamp shade 24 is provided at its upper end with a ring 25 and a washer 26 centrally disposed with respect to the ring 25 50 and supported therefrom by spokes 27. The projections 15 engage the inner peripheral portion of the washer 26 and are forced thereagainst by the pressure exerted by the resiliency of the rings 10 and 11. The flanges 16 effectually prevent the 55 adapter from accidental disengagement with the washer. After the adapter has been secured to the shade, the rings 10 and 11 are sprung over the bulb B and the shade is thereby securely mounted on the bulb.

Figs. 4 and 5 show the adapter employed to mount a ring type shade on a bulb. The ring 28 is secured to the outer shade ring 25 by spokes 27 as with the washer type shade. As shown in these figures, the extensions 15 of the adapter are engaged with the inner peripheral portion of the ring 28.

Fig. 6 shows the ring 28 engaged by the plates 14 of the adapter so that the shade is mounted on the bulb at a lower position than illustrated in Figs. 4 and 5 where the extensions 15 engage the ring 28.

Fig. 7 illustrates the adapter used to mount a bridge type lamp shade on a bulb. As shown, the plates 14 are in engagement with the inner threaded portion 30 of the annulus 31 which is secured to the outer shade ring 25 by the spokes 27. If desired however, the adapter may be disposed with respect to the shade so that the extensions 15 engage the annulus 31, in which event the shade will be mounted on the bulb B in a higher position than as shown in Fig. 7. The ends 17 and 18 of the rings 10 and 11 prevent accidental disengagement of the adapter with the annulus 31.

As shown in Fig. 8, the adapter may also be utilized to secure a ring type lamp shade to a bridge lamp. Bulb B is threaded in a socket 32 supported by the usual bridge lamp arm 33. As shown, the ring 28 is engaged by the extensions 15 but may, of course, as previously mentioned, be engaged by the plates 14 if a lower position of the shade with respect to the bulb is desired. With this arrangement, the shade is supported with the upper end at the contact end of the bulb. This arrangement may also be utilized to mount any shade having a ring to be engaged by the adapter, which is large enough to fit over the bulb socket, on a so-called drop light, that is, on a bulb suspended from a cord or rod or the equivalent supporting means.

From the foregoing, it will be seen that I have provided means whereby any standard type lamp shade may be mounted on an electric light bulb which is supported in any position. And with the exception of the washer type shade, the shades may be mounted on the bulbs at two different heights. The advantages of the adapter to sellers of lamps and lamp shades will be obvious.

It will be apparent that the adapter herein disclosed may be modified so as to provide any given height of the shade with respect to the bulb on which it is mounted and may also be arranged so that more than two different heights may be effected.

Inasmuch as many modifications of the form of the adapter herein disclosed may be made without departing from the principle of the invention, it will be understood that I entertain no intention to limit the invention except by the scope of the claims hereto appended.

What I claim is:

1. An adapter for securing a lamp shade to an electric light bulb comprising spaced resilient ring-like members for engaging opposite parts of an electric light bulb, and plates secured directly to each of said ring-like members, said plates having a portion for engaging the inner annulus of a bridge and ring type shade and another portion of smaller dimension than the first mentioned portion for engaging the washer of a washer type shade, whereby the shade may be securely mounted on the bulb.

2. An adapter for securing a lamp shade to an electric light bulb comprising a resilient bulb engaging portion, oppositely disposed plates secured directly to said portion, each of said plates having a portion for engaging the inner annulus of a bridge and ring type shade and another portion of smaller dimension than the first mentioned portion for engaging the washer of a washer type shade, whereby the shade may be securely mounted on the bulb.

3. An adapter for securing a lamp shade to an electric light bulb comprising a bulb engaging portion and separate lamp shade engaging members secured thereto in fixed and opposed relationship, each of said members having a plurality of shade engaging portions disposed at different elevations whereby the shade may be mounted on the bulb at one of a plurality of different heights.

4. An adapter for securing a lamp shade to an electric light bulb comprising a bulb engaging portion, separate lamp shade engaging members secured thereto in fixed and opposed relationship, each of said members having a plurality of shade engaging portions disposed at different elevations whereby the shade may be mounted on the bulb at one of a plurality of different heights, and means on the lamp shade engaging members for preventing accidental disengagement of the adapter and the shade.

5. An adapter for securing a lamp shade to an electric light bulb comprising a bulb engaging portion comprising spaced resilient wire members each shaped to have oppositely disposed end portions and an intermediate portion for engaging opposite portions of a bulb, and lamp shade engaging members comprising separate plates secured to said oppositely disposed end portions of said wire members, said plates having a plurality of lamp shade engaging portions at different heights whereby the shade may be mounted on the bulb at different heights and having one portion shaped to engage the inner annulus of a bridge and ring type shade and another portion shaped to engage the inner annulus of the washer of a washer type shade.

6. An adapter for securing a lamp shade to an electric light bulb comprising a bulb engaging portion comprising spaced resilient wire members each shaped to have oppositely disposed end portions and an intermediate portion for engaging opposite portions of a bulb, and lamp shade engaging members comprising separate plates secured to said oppositely disposed end portions of said wire members, said plates having a plurality of lamp shade engaging portions at different heights whereby the shade may be mounted on the bulb at different heights and having one portion shaped to engage the inner annulus of a bridge and ring type shade and another portion shaped to engage the inner annulus of the washer of a washer type shade, the oppositely disposed end portions of said wire members and the plates secured thereto normally being disposed a distance apart which is greater than the inner diameter of the annulus of the ring, bridge and washer type shades for which the adapter is intended so that upon engagement of the adapter with a lamp shade, said plates will be urged apart into engagement with said shade.

WILLIAM N. DE SHERBININ.
